R. GOLDSCHMIDT

MECHANICAL HAMMER

Filed July 9, 1925

INVENTOR
Rudolf Goldschmidt,

BY
H.C. Meissner
ATTORNEY

UNITED STATES PATENT OFFICE.

RUDOLF GOLDSCHMIDT, OF CHARLOTTENBURG, GERMANY.

MECHANICAL HAMMER.

Application filed July 9, 1925. Serial No. 42,353.

My invention relates to mechanical hammers wherein rotating eccentric weights are adapted to cause the tup to reciprocate through the action of centrifugal force. In such hammers, the weights and gearing to rotate the same must be all a part of the reciprocating tup where they are subject to the full force of the impact of the blows that are delivered by the tup.

10 In a hammer of the type described in my Patent No. 1,410,010, the tup is reciprocated through the action of two flyweights. In a construction employing four flyweights on the tup, considerable difficulty is encountered 15 in designing the tup and the mountings for the flyweights in a sufficiently rigid structure to withstand the impacts.

It is the object of the present invention to produce a hammer having a tup with four 20 flyweights mounted thereon having a structure that will withstand the shock of the impact.

The present invention may be best understood with reference to the accompanying 25 drawing wherein Figure 1 is a view, partly in section, with parts broken away, illustrating one form of motor-driven hammer embodying my invention, and

Figs. 2, 3 and 4 are modified forms of tup 30 mechanism for use in the casing illustrated in Fig. 1.

Referring to Fig. 1, 11 is an enclosing casing that has a top plate 12 secured thereto by means of bolts 13. Mounted on the 35 casing is a motor 14 to which is attached a handle 15 with a switch operating trigger 16 therein, all of which is a well-known construction.

A shaft 17 is rotated by the motor and 40 has formed integral therewith a pinion 18. A second pinion 19 is keyed to the shaft, and the lower end is seated in a bearing in the frame 21 of the tup.

The pinions 18 and 19 are meshed with a 45 pair of bevelled gears 22 and 23 respectively, each gear having a weight cast integral therewith. The weighted gears 22 and 23 are respectively mounted upon transverse shafts 24 and 25, which in turn are mounted 50 in the frame 21 of the tup.

It will be noted that shafts 24 and 25 extend across the frame and each have a hole 26 therein, to permit the shaft 17 to extend therethrough.

A cross member 27 is secured to the top 55 of the frame 21. The tup 21 carries the guiding lugs 28 that cooperate with stationary guides 29 secured to the casing 11.

A spring 31 is mounted between the top 60 of the casing 12 and the top of the frame or tup 21, so as to impart a unidirectional force to the tup.

The driving shaft 17 and shaft of the motor 14 are connected by a flexible coupling 65 indicated at 32.

Since it is desirable to have the tup and 70 gearing operate in a bath of oil, the casing 11 is closed at the bottom by means of a flexible diaphragm 33 in which is secured an anvil 34.

When a tool 35 is inserted into the hammer, the blows from the tup are transmitted directly to the tool. However, when there is no tool inserted, the blows are received by a cushion 36 that may be composed of a series 75 of leather discs.

In the operation of the hammer, the centrifugal force imparted by the rotating weights causes the frame or tup 21 to reciprocate and the spring imparts a unidirectional force that causes the tup to deliver blows to the anvil 34.

Several different arrangements of tups 80 may be had, one form being shown in Fig. 2 wherein the pinions 18 and 19 are located 85 near the center of the shaft 17. It may also be noted that the frame 21 is formed in two sections that are bolted together at the top and bottom as indicated at 37. The bevelled gears 22 and 23 are each mounted 90 upon a stub shaft 38 that may be formed integral with the frame 21, thus forming a rigid construction for the tup.

It will be noted that the stub shafts 38 are 95 made hollow to form pockets where oil may collect and these pockets are connected through holes 39 with the bearing surfaces of the journals for the gears 22 and 23. The movement of the tup forces the oil into these holes with considerable pressure, particularly when the motion of the tup is suddenly arrested at the moment of impact and at the moment of reversal of the movement from the upper position so that the acceleration and retardation of the tup is used for obtaining forced lubrication of the mechanism, which is very desirable.

Fig. 3 is a sectional view of another modi-

fied form of tup, and Fig. 4 is a view of the tup shown in Fig. 3 taken at right angles to the plane of the tup as shown in Fig. 3.

In Figs. 3 and 4 the shafts 41 and 42, upon which the bevelled gears 22 and 23 rotate, are integral with the tup 21 projecting from the center thereof upwardly. This construction has the advantage that a solid construction is obtained without the necessity of splitting the tup. The pinions 43 and 44 are formed integral with each other, and are keyed to the shaft 17 as indicated by dotted lines in Fig. 3.

In my Patent No. 1,410,010, referred to above, is described a method of splining the pinion to the shaft so that this construction can be used as a guide for the whole tup, rendering the guide members 28 and 29 unnecessary.

Modifications may be made in the arrangement and location of parts within the spirit of my invention and the scope of the appended claim.

I claim:

In a mechanical hammer the combination with an enclosing casing and a motor, of a tup within said casing comprising a frame, a pair of shafts extending transversely of said frame, four weights mounted on said shafts so as to cause the reciprocation of said tup due to the centrifugal action of said weights, gears adapted to rotate said weights, pinions meshing with said gears, a vertical shaft on which said pinions are mounted, said vertical shaft extending through said transverse shafts and connected to said motor.

In testimony whereof I affix my signature.

RUDOLF GOLDSCHMIDT.
